FOLDING CLOSET BOWL

Leif Andersen and Edward A. Fredrickson, Chicago, and Thomas P. Newman, Geneva, Ill., and Hugh R. Van Sciver, Trenton, N. J., and Roy H. Zinkil, Oak Park, Ill.

Application June 18, 1938, Serial No. 214,428

11 Claims.

(Cl. 4—10)

Our invention relates to a type of bowl in which the latter may be pivotably mounted in a manner such that while normally disposed in a concealed and out-of-the-way position, the bowl can easily be withdrawn therefrom and brought to an operative position whenever desired, and also be capable of functioning satisfactorily on relatively small amounts of flushing water.

An important object of our present invention lies in providing for a folding type of closet bowl construction of the general character hereinafter described wherein, for example, the bowl is retainable in a folded position within a cabinet or enclosure and upon actuation of a door or panel 15 or the like forming a part of the said enclosure, the bowl is subsequently unfolded and rendered operative. Conversely, by closing the door or suitably replacing the actuating panel of the enclosing cabinet or structure, the bowl can be 20 made to recede, occupying the space provided for by the enclosure and thus render the latter member concealable from view, as for example, when installed in the compartment or bed room of passenger railway cars, in small apartments or the 25 like.

The details of the novel features applying to the actuating mechanism above referred to are covered in a copending patent application, Serial No. 237,434, filed October 28, 1938, now matured 30 into Patent 2,188,562, granted January 30, 1940.

It is a further important object of our invention to provide a construction in which the closet bowl when withdrawn from the enclosing cabinet or recess and placed in an operative position has 35 its receiving portion automatically water sealed in a manner hereinafter described, and thereby serves to increase the effectiveness of the subsequent flushing therefrom, even considering its installation upon railway cars and the like where 40 the available water supply will necessarily be limited.

Another object lies in providing in a closet bowl for a hollow sleeve or trunnion type of supporting means whereby the relatively fragile earthenware 45 member, such as the bowl itself, is securely supported upon the said trunnion member and is suitably reinforced by the supporting means so as to minimize the dangers from shock, vibration and the like, with its otherwise deleterious effect 50 upon the ware.

Another object is to provide in this type of device for adjustable stop means for accurately and conveniently leveling the bowl in its operative position thereby conveniently allowing for any irregularities encountered in the initial installation.

Another important object lies in the provision of a construction in which the bowl supporting trunnion member serves as a leak-proof mount 55 during the course of operation and also provides

unitarily for both the inlet supply to the fixture as well as for the discharge therefrom, in addition to the important function of serving as a substantial shut-off for the inlet supply at a predetermined pivotal position of the closet bowl. 5

Another object lies in providing for a means of discharge from the fixture and into the trunnion member whereby a rapid and effective siphonic flushing action will be obtained incidental to the 10 actual discharge, thereby furthering the sanitary functioning of the fixture.

Another object lies in the provision for a base or support for the fixture whereby the latter, as a complete unit, may be assembled and applied to the installation conveniently, including the 15 necessary valves, actuating mechanism and base member for the mounting thereof as a unit, thus enabling the manufacturer to ship the fixture as an assembled unit with the flushing mechanism 20 properly adjusted, based upon factory tests.

Other objects and advantages will become more readily apparent upon proceeding with the following specification in connection with the drawings, in which

Fig. 1 is a side exterior view slightly in plan 25 perspective of a folding closet bowl embodying our invention and which bowl in this view is shown in the lowered and operative position.

Fig. 2 is a front exterior perspective view partly in plan perspective in which the closet bowl is 30 shown in its folded and inoperative position.

Fig. 3 is a plan exterior view of the closet bowl and base assembly showing the space-saving manner in which the closet bowl is preferably positioned with relation to its mounting base so 35 as to allow for sufficient space for the necessary control fixtures without requiring extra space provisions therefor within the cabinet or enclosure.

Fig. 4 is a rear, partly exterior view showing a 40 preferred method in which the discharge return bend is applied to the fixture support, and showing in fragmentary section the manner in which the journally mounted trunnion or sleeve member is position with relation respectively to the 45 inlet supply, the discharge outlet and the actuating mechanism for revolvably moving the trunnion.

Fig. 5 is a side exterior view showing in solid lines the closet bowl in its operative and lowered 50 position and in dotted lines indicating the inoperative and folded position.

Fig. 6 is a magnified fragmentary sectional view taken on the line 6—6 of Fig. 2, showing principally the trunnion member inlet and discharge 55 passages and the end mounting thereof with relation to the actuating mechanism.

Fig. 7 is a fragmentary sectional view of the dual flushing and bowl sealing valve serving the joint purpose for accomplishing the discharge 60

flushing of the fixture as well as for subsequently providing for an immediate water seal or refill for the bowl portion of the fixture when the latter is lowered and is placed in position for use.

5 Fig. 8 is a side fragmentary sectional view of the sealing refill portion of the dual valve and which constitutes the right-hand portion of the dual valve described in Fig. 7.

10 Fig. 9 is a schematic outline of the water flushing arrangement, tracing the path of water flow from the inlet, past the stop valve, through the dual valve respectively and thence into the passages defining the jet flush and the rim flush of the fixture.

15 Similar reference characters refer to similar parts throughout the various figures.

Referring to Fig. 1, the folding closet bowl generally designated as 1 is illustrated as being provided at its base portion with a conduit 2 having connection with a suitable source of water supply (not shown) and with the direction of the water flow being taken as indicated by the arrow. Preferably, but not necessarily required, in connection with the control of such water supply, a stop valve 3 is provided so that in the event it is necessary to make adjustments, repairs or inspection of the fixture, the stop valve may be used to shut off the water supply to the fixture. The latter valve is attached by means of a suitable pipe connection 4 to the lower chamber of the trunnion base 5. The latter member is preferably provided with an extension 6 of the said hollow chamber which, by means of the bolting member 7, serves to hold the latter in fixed position with relation to the floor plate 8.

As previously mentioned, the closet bowl is pivotally mounted upon a rotatable hollow trunnion and with this in mind reference is made to Fig. 6 in which the said hollow chamber of the trunnion base 5 is shown as being connected with the inlet 4. The trunnion base member 5 is provided with a port or passage 9 through which the water passes from the hollow chamber and thence leads upwardly into the housing 10. The latter housing interiorly is provided with a cylindrically machined bearing portion 11 within which the hollow trunnion shaft 12 is journaled for limited rotative movement. The said trunnion shaft 12 is made with a cylindrically formed 50 longitudinally extending passage 13 and on its lower periphery has the circular aperture 14. In the lowered and operative position of the closet bowl, the aperture 14 coincides with the similarly shaped passage 9 thereby serving as a port 55 through which the water enters the interior of the hollow trunnion shaft 12. When the bowl is in its inoperative and upwardly folded position, the aperture 14 will have been moved in a clockwise direction (viewed from end of trunnion), 60 and accordingly the walls of the shaft 12 serve to substantially shut off the connection between the passage 9 and the trunnion passage 13, thus enabling the trunnion to function as a sleeve valve. The bearing portion 11 is interrupted so 65 as to provide for an enlarged recess 15 serving as a stuffing box for the packing 16 in which co-operating therewith is a bolted gland 17 exerting the desired compression upon the stuffing box packing by means of the bolts 18. Thus a 70 journaled leak-proof bearing for one end of the trunnion shaft is provided.

On its upper portion, the housing 10 is conveniently provided with an apertured lug or ear 19 having for its object a purpose hereinafter described in greater detail in connection with

the dual valve flushing means. Continuing with a detailed description of the bowl supporting trunnion, beyond the stuffing box the hollow shaft 12 is suitably enlarged as at 20 thereby forming the end chamber 21 within which the inlet supply flow is directed upwardly into an outlet 22. The latter outlet is connected with the flexible tubing 23 leading therefrom by means of the threads 24 and the locknut 25 to form a joint as indicated.

10 As more clearly shown in Fig. 1, the flexible tubing 23 communicates with the dual control valve, generally designated 26, for the flushing of the bowl and afterwards sealing the same, and which is connected thereto by means of the 15 union ring 27. The dual valve 26 is provided with the inlet port 28 leading to the successively arranged and interconnected chambers 29 and 31 respectively. The dual valve, having the mounting pad 30, is rigidly attached to the side of the 20 bowl by means of the bolts 32. Obviously, depending upon the nature of the installation, the attachment of the dual valve may be on the right or left side with the bowl selected for the attachment pad accordingly.

25 At this stage of the description it is desirable, in general, to understand the path of the inlet water within the dual valve on its way to the bowl, and therefore reference is now made to Fig. 7, showing the internal construction of the 30 valve proper. The casing of the dual valve is divided into two chambers, as indicated, both of which are interconnected, as previously mentioned, by means of the port 33, forming the wall connection between the two in view of the partition wall 34. At the lower portion of the casing, the respective hollow chambers 35 and 36 are thereby provided having outlet ports 37 and 38 respectively, each leading to the inlet manifold of the bowl 1. Of course, with the valves in the 40 closed position, as illustrated, these lower valve chambers are devoid of any water passing from the inlet supply passage 28 and until each valve is actuated, as hereinafter described, the bowl likewise receives no water through the passages 45 37 and 38. The bowl is provided with the conventional manifold 40 in its inlet supply chamber which is not shown in detail but which is designated diagrammatically in Fig. 9. It suffices to say that so far as this invention is concerned, 50 the bowl manifold has passageways leading respectively to the rim flush 39 and to the jet flush 41 within the bowl 1. The detailed manner of accomplishing the successive operations of the 55 dual valve 26 in its application to the flushing and sealing of the bowl, will be described at length later in the specification.

Thus far the description of the hollow trunnion shaft mounting has been concerned only with that function having to do with the inlet 60 supply of water to the closet bowl through the respective passages and valves to the manifold leading to respective passages to the bowl rim flush, jet and seal. But, as mentioned, the trunnion serves also to handle the outlet or discharge 65 from the bowl.

Therefore, reverting again to Fig. 6, and continuing with the description of the hollow trunnion shaft, the enlarged portion of the hollow trunnion shaft 12, as previously designated at 20, is provided with an enlarged extension 42 which is separated from the previously described fresh water inlet chamber 21 by means of a wall or partition 43 and also having a substantially round port 44 extending transversely 70 75

thereto. The said port 44 thereby forms a side passage into the hollow trunnion for a connection by means of a bolted flange 45 to a return bend 46, the latter member being attached thereto by means of the integral bolted flange 47 and the bolts 48 (see Fig. 5). It will be noted further that the return bend 46 is of substantially U-form, as shown more clearly in Fig. 5, and extends upwardly and then forwardly so as to connect with a similar flange 49 and the bolts 50 and the nuts 51. The return bend 46 beyond the flange 49 is provided with an annularly-formed extension or lip 52 which abuts against the rearwardly extending discharge outlet of the closet bowl 1 in a conventional tongue-and-groove connection, as indicated at 53. The discharge outlet portion of the bowl 1 is provided with a complementary companion flange 54 whereby the bolts 50 may be held rigidly by the joint means provided by the nuts 55 and the cap screw 56 thus forming a liquid-tight joint at 53. The connection currently described in cooperation with the return bend 46 provides for the necessary discharge of the contents from the interior of the bowl proper passing into the return bend which communicates with the side opening 44 of the trunnion shaft and then flowing into the interior passage 57 of the enlarged portion 42 of the bowl supporting trunnion shaft.

At this stage, the flow of the bowl contents is facilitated perceptibly by the arrangement of a compound turn simulating siphonic flow through a closet trap and is accomplished by the relation of the longitudinally extending discharge passage 57 with the discharge inlet port 44. A flow wiping action is obtained within the trunnion passage particularly when the flow strikes the fillet 12a after being deflected slightly upwardly by passing over the arcuately positioned ridge 12b, and then passing into the downwardly extending passage 78 connected with the passage 83 of the plate 8.

As to the external mounting of the enlarged end of the hollow trunnion shaft 12, in order to accommodate the necessary discharge capacity, the said trunnion shaft is suitably enlarged at its peripheral bearing 58 within the opposite trunnion journaling member 59. It is further provided with a cylindrically formed, preferably machined bearing which is rendered substantially leak-proof by the stuffing box packing 61 compressed within the recess 62 by means of the gland member 63 acting in cooperation with the stuffing box nut 64. In order to further assure of a liquid-tight seal at the transversely extending end portion 12c of the bearing 58, a gasket 65 is preferably interposed between the said end face 12c of the trunnion bearing and the inner end face of the enlarged portion trunnion journaling member 59. Projecting preferably integrally from the end face 12c, an actuating shaft 66 is provided for the transmission of the desired rotation to the hollow trunnion shaft 12. To accomplish such actuation, a bevel gear 67 is mounted thereon and pinned in non-rotatable relation by means of the lockwasher 68 and the respective locknuts 69 and 70, meshing with a similar bevel gear 71 suitably mounted, as at 72, upon the extension 73 of the trunnion bearing 59 and held non-rotatably to the shaft 75 by means of the pin 60. An actuating hub member 74 is non-rotatably mounted upon the journaled rod 75, the said actuating hub having a lever extension 76 which is suitable for attachment to a lever and hinged connection, as at 77, for such ac-

tuation means as may be necessary to rotate the respective bevel gears and in consequence thereof to rotate the hollow trunnion shaft 12 in its reduced bearings 66 and 11 respectively.

Since the closet bowl 1 is fixedly mounted upon the trunnion shaft, as previously referred to, by means of a side outlet connection with the return bend 46 and the bracing support, as herein-after described, whatever rotation of the trunnion occurs will likewise cause the said closet bowl to be moved arcuately either upwardly or downwardly, depending upon its previous position and the direction of rotation of the actuating shaft 75. A disclosure setting forth a preferred method of accomplishing the actuation of this type of a closet bowl is covered by our previously referred to co-pending patent application.

The lower peripheral portion of the enlarged end 42 of the trunnion member 12 being provided with the downwardly extending aperture 78, connects with the passage 79 within the trunnion member 59. The latter member is mounted upon the floor or base plate 8 and is attached thereto by means of the flange member 81, compressing the gasket 82 to form a joint and leading into the discharge passage 83 of the floor plate 8 which discharge passage may lead to such means for sewage disposal as may be provided. The latter member is suitably formed with the hollow pan-like portion 84 so that when, as indicated in Fig. 5, the closet bowl is placed in a folded position, there may be sufficient clearance so that the return bend 46 may be accommodated in the said position.

It has not been deemed necessary that the internal structural details of the closet bowl should be shown or described herein because its particular functioning with relation to the present invention is not indispensable, and it is sufficient to say that the closet bowl herein referred to has the usual inner manifold passages leading respectively to the bowl rim flush and the jet discharge. Points of novelty reside in certain phases of the internal construction which are being covered in a separate patent application being currently filed and identified as Serial No. 219,504, filed July 16, 1938.

Referring now to Fig. 1, in order that the bowl in its lowered and operative position, as shown, may be conveniently and accurately positioned in a level plane with relation to the usual water seal, the trunnion journaling member 59 is provided preferably with an integral lug 85 and an adjusting screw 86 with threads 87a whereby the trunnion member may be adjustably rotated to a predetermined desired position with the screw serving as an adjustable stop therefor shouldering as at 81, the latter member being more clearly shown in Fig. 2.

Continuing with Fig. 2, in order to support properly the somewhat substantial overhang of the closet bowl, it is preferable that the bowl 1 should be provided with a transversely extending integral lug 88 provided with an aperture to serve as anchoring means for the bolt 89, the latter member being attached to the integral lug 91 of the enlarged portion 42 of the trunnion 12 using the nuts 92 for maintaining the supporting bolt 89 rigidly in position.

Reference has been made previously herein to the fact that an important element of our invention lies in automatically sealing or filling the closet bowl to a certain predetermined level immediately upon lowering the bowl to its opera-

- tive position and before actual usage may occur. This is accomplished by a novel arrangement of an actuating mechanism for a flush valve which is employed separately for the purpose and which, as also stated previously, forms a part of the dual valve 26, the other portion of which functions as the flush valve. Therefore, reverting now to Fig. 7, a significant part of our invention resides in the means taken not only to flush the closet bowl in its lowered and operative position but also to automatically provide for the said water seal of a predetermined amount and depth immediately upon having the bowl lowered to its operative position.
- 15 The internal mechanism of the dual valve is of the type known as the non-hold-open and which, as further described, operates to flush and to seal the bowl by tilting the actuating stem thereof to one side. As will be hereinafter set forth more clearly, when the actuating stem is thus moved, the valve and the stem are lifted by the water pressure acting beneath the peripheral limits of the valve.
- 20 As to a general description of and the manner of functioning the combined flushing and sealing valve 26, the union ring connection 27 attached to the valve is connected to the flexible tubing 23 which, as previously stated, in proper sequence receives the water supply by means of the hollow trunnion shaft 12 and the trunnion bearing 10 from the inlet conduit 2. The water upon entering the inlet passage 28 then passes into the respective upper valve chambers 29 and 31 by means of the inlet bleed holes 93 and 94 respectively in each valve, thus permitting the flushing water to pass into each of the chambers 95 and 96 above the pistons of each of the valves within which the respective springs 97 and 98 are positioned, functioning to place the auxiliary valve members 99 and 101 in each of the respective closure members in normally seated position, as shown.
- 25 To observe the detailed method of operation of the valves, first as to the bowl flushing method used and later as to the bowl sealing and refill method, let it therefore be assumed that the flushing mechanism of the valve is to be operated in which case the pedal member 102 (Fig. 7) is depressed thereby causing the lever 103 to be moved inwardly and to contact with the head 104 of the horizontal member 105, causing the latter member to move forward against the action of the spring 106. The said horizontal member is journaled within the bearing of the gland 107 and the stuffing box 108 and upon such forward movement contacts with the telescoping member 109 tilting the latter to one side so as to cause the auxiliary valve member 101 to leave the seat 111. The water already above the auxiliary valve 101 is thereby permitted to descend past the said valve, thereby relieving the pressure of the water also on the main valve 112 in chamber 31 which is exerted on the surface 113 and also against the cup leather 114 but which is not relieved. Such release of the pressure in chamber 31 causes the main valve to rise from its seat 115 and thereby permits the water to pass through the seat opening 116 and into the passage 38 in which, by means of the bowl manifold 40 schematically referred to in Fig. 9, the water flows under line pressure respectively to the bowl rim flush and to the jet flush of the bowl 1. Then in accordance with the principle of operation provided by this construction, and regardless of whether or not the pedal is continuously depressed, due to

the telescoping movement of the auxiliary valve stem within the member 109, the main valve and the auxiliary valve members are permitted to return to their respective seats.

The latter action of the auxiliary valve members 101 causes the water pressure to accumulate within the chamber 31 and thereby causes the main valve closure member 112 to descend to its seat, and so the setting of the valves is ready for another cycle of operation. Mention is made at this point that the detailed construction of the internal valve mechanism, as just described, is not a part of our invention and its detailed principle of operation for purpose of reference is more completely set forth in expired United States Patent No. 1,114,398 granted October 20, 1914.

After use and the subsequent flushing of the closet bowl has been accomplished, as hereinabove described, the latter may then be folded upwardly into the cabinet or recess and the like, 20 in the position as indicated in Figs. 2 and 5. However, upon being unfolded and brought down again into a lowered and operative position it becomes desirable, for sanitary reasons, that the bowl should immediately be supplied before use 25 with an adequate water seal or refill within the receiving chamber adjacent to the jet flush 41. Accordingly, the latter result is provided preferably by means of the actuating chain 120 which at one end thereof is attached to the integral 30 connecting lug 19 mounted upon the upper portion of the trunnion housing 10 and is connected to the bifurcated member 117 by means of the screw 118 and the adjustable link 119, while the other end of the chain 120 is attached to the tiltable bifurcated link 121 integrally connected to the actuating member 122 of the refilling valve mechanism. It will therefore become apparent that as the bowl is drawn pivotally downwardly and unfolded upon its trunnion and ultimately 40 assumes a horizontal position, the chain 120 will become taut, being fixedly attached at the end mounted upon the trunnion housing 10, and draws upon the link 121 causing the tilting of the horizontal member 122. Such tilting of the latter member causes the member 104 to be moved axially inwardly sufficiently for its stem portion 105 to contact with the telescoping member 109 (see Fig. 8) and thereby set in motion a cycle of operation of the internal valve mechanism comprising an auxiliary valve member and a main valve member in the same manner as described in connection with the operation of the foot lever 102.

Obviously, in view of the differences in purpose 55 of the respective valves, such as the pedal operated in one case and the chain operated in the other, there may be slight changes made in the detailed structure. For example, because the amount of water necessary for supplying the refill and maintaining a water seal in the closet bowl in its horizontal and operative position will necessarily not require as great a volume of water as in the flushing of the bowl, the main valve in the former may be provided with a lip or shoulder 60 123 for the purpose of throttling or reducing the amount of water flowing past the main valve when the latter is in its open or unseated position.

Referring to the schematic outline of water 70 flow in Fig. 9, the flow through the passage 38 of the flushing portion of the valve, in relation to the manifold 40 of the bowl, will preferably pass in a larger proportion to the jet 41, while for the refill or sealing valve, the larger percentage of 75

flow through the passage 37 will pass through rim flushing apertures collectively designated as 39.

Thus it will be apparent that we have devised 5 in a relatively simple manner a folding bowl construction capable of being rigidly mounted for pivotal movement, adequately flushed and refilled for further use and capable of being easily accommodated within a recess or cabinet.

10 While a single preferred embodiment of our invention has been described, it should be readily understood that our invention is capable of a great variety of modifications. Therefore, 15 changes in the construction and in the arrangement of the various parts may be made without departing from the spirit or the scope of the invention as determined by the claims appended hereto.

We claim:

20 1. In a folding type closet bowl having jet and rim flush means, supporting means for the said closet bowl, the said supporting means comprising a hollow trunnion member having connections respectively to a source of supply and discharge means, valve means for the said jet and rim flush cooperating with the said trunnion member, and independent valve means for providing a refill within the said bowl upon the latter member being lowered to an operative position.

25 2. In a folding type closet bowl, supporting means for the said closet bowl, the said supporting means comprising a hollow trunnion member having connections respectively to a source of supply and discharge means, and valve means for providing a water seal within said bowl from the said source of supply, the said valve means being rendered operative upon lowering of the said latter member.

30 3. In a folding type closet bowl, supporting means for the said closet bowl, the said supporting means comprising a hollow trunnion member having connections respectively to a source of supply and discharge means, valve means provided by the said trunnion member for effecting a shut-off between the said bowl and the said source of supply upon occurrence of predetermined rotative movement of the said trunnion member, independent valve means cooperating with the said trunnion member, connecting means 35 interposed therebetween, the said connecting means being positioned substantially transversely to the longitudinal axis of the said trunnion member.

35 4. In a closet bowl mounted for swinging movement in a substantially vertical plane, supporting means for the said closet bowl, the said supporting means comprising a hollow trunnion member having connections respectively to a source of supply and a discharge means for the said bowl, the said discharge means including a return bend member connecting the said bowl with the trunnion member.

40 5. In a closet bowl mounted for swinging movement in a vertical plane, combined supporting means for effecting the swinging movement of the said closet bowl, a curved member connecting the said bowl with the said supporting means, the said supporting means comprising a hollow trunnion member having inlet means to a source of water supply and including inlet and outlet means for effecting the discharge from the said bowl, the said latter means cooperating with the said curved member to produce a substantially siphonic discharge from the said bowl.

45 6. In a folding type closet bowl having respec-

tive jet, rim flush and refill means, the said latter means comprising independent valve means manually and automatically operative respectively, pivotable supporting means for the said closet bowl, the said supporting means comprising a 5 substantially horizontally disposed hollow shaft member having chambered end supports respectively connected to a source of supply and discharge for the said bowl, the said manual portion of said valve means providing for the said 10 jet and rim flush, the said automatic valve means providing a refill within the said bowl upon the latter member being positioned operatively.

7. In a closet bowl having jet and rim flush means mounted for swinging movement in a substantially vertical plane, supporting means for the said closet bowl, the said supporting means comprising a hollow trunnion member having connections respectively to a source of supply and discharge for the said bowl, valve means for the 20 said jet and rim flush, and automatic valve means for providing a refill within the said bowl, the said automatic valve means having actuating means positioned between the said valve and the said trunnion member whereby upon lowering the 25 said bowl to a predetermined position the said automatic valve means is operated.

8. In a folding type closet bowl, supporting means for the said closet bowl comprising a hollow trunnion member having independent passages respectively to a source of supply and discharge for the said bowl, the discharge passage having means extending across a portion of its periphery whereby the flow therethrough into a 30 downwardly extending portion of the discharge is 35 facilitated.

9. In a closet bowl, supporting means upon which the said bowl is mounted for swinging movement in a vertical plane, the said supporting means comprising a hollow trunnion member 40 being provided with divided chambers communicating respectively with a source of supply and discharge for the said bowl, combined valve means for effecting the flushing and the refilling of the said bowl, the said bowl refilling means 45 being operative only upon the said valve means being moved relatively to the said supporting means.

10. In combination, a self-closing valve having respective means to manually and to automatically operate the said valve, a folding type closet bowl having respective jet, rim flush and refill means, the said valve having connections leading respectively to a source of supply and to the said bowl, the said manual portion of the 55 said valve providing for the jet and rim flush to the said bowl, the said automatic means of the said valve providing for a refill or seal within the said bowl when the latter member is moved from an inoperative position to an operative 60 position.

11. In a folding type closet bowl, supporting means for the said closet bowl, the said supporting means comprising a hollow trunnion member having connections respectively to a source of supply and discharge means, the said trunnion member having a partition between the passages thereof defining the said source of supply and the said discharge means.
